CLAIM

The ornamental design for a handbag, as shown and described.

DESCRIPTION

FIG. 1 is a perspective view of a handbag showing my new design;

FIG. 2 is a front elevational view;

FIG. 3 is a right end elevational view;

FIG. 4 is a bottom plan view thereof; and

FIG. 5 is a top plan view thereof.

The characteristic feature of the design resides in the surface ornamentation of the handbag.
